STREET LIGHTING LAMP OR THE LIKE

Kenneth F. Guggemos, Winsted, Minn.

Application May 27, 1957, Serial No. 46,607

Term of patent 14 years

(Cl. D48—31)

Fig. 1 is a side elevational view of a street lighting lamp or the like, showing my new design;

Fig. 2 is a top plan view thereof; and

Fig. 3 is a cross sectional view to a larger scale taken on line 3—3 of Fig. 1.

I claim:

The ornamental design for a street lighting lamp or the like, substantially as shown.
